UNITED STATES PATENT OFFICE.

JOHN REGAN, OF NEW BEDFORD, MASSACHUSETTS, ASSIGNOR TO CROMPTON & KNOWLES LOOM WORKS, OF WORCESTER, MASSACHUSETTS, A CORPORATION OF MASSACHUSETTS.

WARP-STOP-MOTION CLAMP.

1,355,909.

Specification of Letters Patent. Patented Oct. 19, 1920.

Application filed June 3, 1920. Serial No. 386,288.

To all whom it may concern:

Be it known that I, JOHN REGAN, a citizen of the United States, residing at New Bedford, in the county of Bristol and State of 5 Massachusetts, have invented a new and useful Warp-Stop-Motion Clamp, of which the following is a specification.

This invention relates to a clamp or holding device for a warp stop motion of the 10 type in which a number of longitudinally extending bars are used, such as are shown in my prior Patent No. 1,265,112, issued May 7, 1918.

When such warp stop motions are used 15 in broad looms, it is advisable to provide some form of clamp or support at one or more intermediate points to prevent vibration and to hold the parts in operative relation.

20 It is the object of my invention to improve and simplify the construction of such clamps, at the same time reducing the cost of manufacture.

More specifically my invention relates to 25 certain arrangements and combinations of parts which will be hereinafter described and more particularly pointed out in the appended claims.

A preferred form of my invention is 30 shown in the drawings in which—

Figure 1 is a side elevation of my improved clamp, certain parts being broken away;

Fig. 2 is a sectional plan view taken along 35 the line 2—2 in Fig. 1;

Fig. 3 is a top plan view of the device;

Figs. 4 and 5 are end elevations looking in the direction of the arrows 4 and 5 in Fig. 1, and

40 Fig. 6 is a detail sectional view taken along the line 6—6 in Fig. 1.

Referring to the drawings, I have shown a plurality of separator bars 10 and guide bars 11, such as are found in my prior patent previously noted.

My improved clamp consists of three simple pieces of metal, namely, a plate 12, a binding rod 13, and a cross bar 14.

The plate 12 is preferably stamped from 50 heavy sheet metal and is provided with notches or recesses 15 and 16, to receive the separator bars 10 and vibrator bars 11 respectively. The binding rod 13 underlies the separator bars 10, and is provided with 55 threaded up-turned ends fitting against the

ends of the plate 12. The cross piece 14 is also preferably formed of a single piece of sheet metal, bent to the U-shaped section shown in Fig. 6, and fitting over the upper edge of the plate 12.

At its two ends the cross bar 14 is slotted to permit free passage of the ends of the rod 13. The slot at one end of the cross bar is closed as shown in Fig. 5, while the slot at the opposite end is open as shown in Fig. 4.

60 Binding nuts 17 on the threaded ends of the bar 13 constitute means for forcing the bar 14 against the plate 12 and securely holding the parts in position.

When the nuts 17 are loosened, the cross bar 14 may be slipped endwise, so that its open end will be disengaged from the binding rod 13. The cross bar may then be swung around the opposite end of the rod 13 as a pivot and all parts of the device may 75 then be removed from the stop motion if desired.

I have thus provided a clamp of simple construction, embodying very few parts 80 which are all easy to manufacture. The device is found satisfactory and efficient for the purpose for which it is designed.

Having thus described my invention, it will be evident that changes and modifications can be made therein by those skilled in the art, within the spirit and scope of my invention as set forth in the claims, and I do not wish to be otherwise limited to the details herein disclosed, but what I claim is:—

1. A clamp for a warp stop motion, comprising a spacing member, a continuous rod inclosing said member on three sides, a cross bar fitting over the top of said spacing member, and means to bind said parts together.

90 2. A clamp for a warp stop motion having a plurality of longitudinally extending separator bars and vibrator bars, comprising a rigid plate recessed to receive said several bars, a continuous binding rod inclosing said plate on three sides, a cross bar, and means on said rod to seat said cross bar against the upper edge of said plate.

95 3. A clamp for a warp stop motion having a plurality of longitudinally extending separator bars and vibrator bars, comprising a rigid plate recessed to receive said several bars and supported thereby, a binding rod underlying said bars and having threaded portions extending upward along the two ends of said plate, a cross bar of U-shaped 100 105 110

section pivoted on said rod and resting on said plate, and binding nuts for said cross bar threaded on the up-turned ends of said rod.

- 5 4. A clamp for a warp stop motion having a plurality of longitudinally extending separator bars and vibrator bars, comprising a rigid plate recessed to receive said several bars and supported by said separator bars, a wire rod underlying said bars and having threaded portions extending upward

along the two ends of said plate, a cross bar formed of one piece of sheet metal bent to fit over the upper edge of said plate, and means to bind all of said parts together, said cross bar being slotted at each end to receive the ends of said wire rod, one slot being open and the other closed at its outer end. 15

In testimony whereof I have hereunto affixed my signature.

JOHN REGAN.
